UNITED STATES PATENT OFFICE.

GEORGE C. SNYDER, OF NEW YORK, N. Y., ASSIGNOR TO THE THREADLESS BUTTON COMPANY.

CARRIER-TAPE.

1,258,715.

Specification of Letters Patent. Patented Mar. 12, 1918.

Application filed February 2, 1916. Serial No. 75,741.

To all whom it may concern:

Be it known that I, GEORGE C. SNYDER, a citizen of the United States, and resident of the city, county, and State of New York, have invented certain new and useful Improvements in Carrier-Tape; and I do hereby declare the following to be a full, clear, and exact description of the invention, such as will enable others skilled in the art 10 to which it appertains to make and use the same.

This invention relates to carrier-tapes for fasteners of the kind employed by dress-makers, the tapes being sewed along the 15 meeting edges of the garments to thereby apply the fasteners to the garment for the entire length of the opening at one operation.

Such fastener-carrying tapes are well 20 known and have been in the market for some time. The tapes are supplied in different weights for fabrics of different kinds, it being necessary that the tape approximate in weight the weight of the cloth to which it is 25 applied as it is well known that if a heavy piece of cloth be sewed to a piece of much lighter weight the threads will pull out of the lighter piece and tear it.

It has heretofore been impossible to apply 30 these fasteners by means of tape to thin fabrics used for evening gowns, light waists, etc., for the reason that if the tape is thick enough to afford sufficient anchorage for the fastener it is too heavy to be sewed to 35 the fabric.

This is particularly true of fasteners of the kind known as "threadless buttons" which are composed of two flanged parts adapted to be clamped together through a 40 hole in the fabric with their flanges on opposite sides of the fabric. For these fasteners the tape must be of substantial weight or else the fasteners will very readily pull out of the tape.

The object of the present invention is to 45 provide a fastener-carrying tape particularly for the threadless button type fastener, which may be sewed to fine fabrics without danger of tearing and will at the same time supply an anchorage for the fastener of 50 sufficient strength to prevent its being torn loose by the strain on the fastener to which it is subjected in use.

My invention also has the additional object 55 of providing a tape into which the

trade-mark or other name to be applied to the article may be advantageously woven as an integral part of the tape. With thin material, light enough in weight for attachment to sheer fabrics, there are not sufficient 60 layers of thread in the fabric to weave in the name so that if the name is to be applied to such fabric it must be applied by letters formed of stitches or embroidered lines. Tape with the name so applied presents an unsightly appearance because of the much greater thickness where the name is applied, and the fabric is also materially weaker at such points as will be readily understood. With my improved tape the portions 70 bearing the name have no greater number of threads than other portions of the tape, the name does not stand out in an unsightly manner, and the tape is of uniform strength throughout. 75

In the accompanying drawings, I have illustrated my improved tape with the fasteners attached and in said drawings,

Figure 1 is a plan view of the tape twisted to show both sides thereof; 80

Figs. 2 and 3 are sectional views on a greatly enlarged scale on lines 2-2 and 3-3 respectively of Fig. 1;

Fig. 4 is a plan view of a portion of the fabric with the threads spread apart to show 85 the manner in which the name is made to appear in the fabric; and

Fig. 5 is a longitudinal section on line 5-5 of Fig. 4.

Referring to the drawings, 1 indicates the 90 edge portions of the tape which are of the usual weave and are formed of thread sufficiently light for attachment to dress-goods of the character above described. Along the center of the tape there is provided a reinforced portion or "stripe" 2 formed of extra threads 3 which are woven into the tape in the manner shown in the diagrammatic views of Figs. 2, 3, 4 and 5. As here shown, the extra threads 3 are woven into 95 the tape so as to be visible on one side only throughout the portions between the points where the trade-mark or other name appears, each thread 3 underlying one of the longitudinal threads 3^a in the body of the 100 tape. To form the name some of the extra threads 3 are twisted over the threads 3^a as shown in Figs. 4 and 5 in the outline of the letters of the names so that the name appears in raised letters 5 on the side of the 110

tape opposite to the raised reinforcing "stripe".

The fasteners 4 comprise two parts 6 and 7, having flanges at their bases which are 5 clamped to the opposite sides of the tape as shown in an enlarged section in Fig. 2. The width of the reinforcing "stripe" will be greater than the diameter of the flanges of the fasteners so that the fasteners will 10 be anchored entirely in the middle portion of the tape. The extra thread 3 which forms the reinforcing stripe may differ slightly in shade from the main body of the tape to make the letters of the trade-mark 15 appear clearly.

The thin edges of the tape are of sufficient width to take the stitches by which the tape is sewed to the cloth of the garment so that there will be no strain on the 20 garment such as is usually produced by sewing to it a heavier piece of cloth.

It will also be noted that the tape is of uniform strength throughout its entire length. The weaving in of the letters of the 25 trade-mark does not affect the strength of the tape, as the same number of threads are used in the letters as in the rest of the stripe, the threads being merely on the opposite side of the tape.

30 It will of course be understood that the weave selected for illustration is shown by way of example only; that the number of threads added to form the stripe may be varied and the size and quality of the 35 threads may be different in the stripe and body of the tape without departing from the spirit of the invention.

I claim:

1. A fastener-carrying tape consisting of 40 longitudinal threads and transverse threads woven together throughout the width of the tape, the central portion of the tape being provided with extra longitudinal threads underlying the first named longitudinal threads and held in place against the first 45 named longitudinal threads by transverse

threads, said extra threads forming a central reinforced strip to provide anchorage for the fastening devices.

2. A fastener-carrying tape consisting of 50 longitudinal threads and transverse threads woven together throughout the width of the tape, the central portion of the tape being provided with extra longitudinal threads lying beneath the longitudinal threads and 55 along one side of the tape for stretches of the tape of considerable length to form a central strip of sufficient strength to provide anchorage for the fastening devices, said extra longitudinal threads being brought 60 above the first named longitudinal threads at intervals to form designs or marks on the upper side of the tape.

3. A fastener-carrying tape consisting of 65 longitudinal threads throughout the body of the tape, extra threads extending longitudinally through the central portion of the tape adjacent to and directly beneath the first named longitudinal threads to form a reinforced strip to which fastening devices 70 may be attached, and transverse threads woven about both sets of longitudinal threads in the central portion of the tape and about the first named longitudinal threads at the side portions of the tape. 75

4. A fastener-carrying tape comprising a body portion formed of longitudinal threads and transverse threads, and a central reinforced portion to provide an anchorage for fastening devices, said central portion being 80 formed of extra threads extending longitudinally through the central portion of the tape and lying adjacent to and beneath the first named longitudinal threads for stretches of tape of considerable length and being carried above said first named longitudinal threads at intervals to lie upon the upper surface of the tape to form a design or mark thereon. 85

In testimony whereof I affix my signature. 90

GEORGE C. SNYDER.
